CLIMBING EXERCISE PEGBOARD

Jack E. Gregory, Spokane, Wash., assignor to J. E. Gregory Co., Inc., a corporation of Washington

Filed Oct. 10, 1967, Ser. No. 8,942

Term of patent 14 years

(Cl. D34—5)

FIG. 1 is a perspective view of a climbing exercise pegboard embodying the instant design;

FIG. 2 is a front view of the climbing exercise pegboard;

FIG. 3 is a side view of the climbing exercise pegboard.

The pegs are an integral part of the board.

The undisclosed side of the climbing exercise pegboard is a mirror image of the side shown. The rear of the climbing exercise pegboard is planar and bears no decoration.

I claim:

The ornamental design for a climbing exercise pegboard, as shown and described.
